UNITED STATES PATENT OFFICE.

GEORGE F. KLEMM, OF PHILADELPHIA, PENNSYLVANIA.

GLOBE-HOLDER FOR BURNERS.

SPECIFICATION forming part of Letters Patent No. 734,569, dated July 28, 1903.

Application filed April 24, 1903. Serial No. 154,085. (No model.)

To all whom it may concern:

Be it known that I, GEORGE F. KLEMM, a citizen of the United States, residing at the city of Philadelphia, in the county of Philadelphia and State of Pennsylvania, have invented certain new and useful Improvements in Globe-Holders for Gas-Burners, of which the following is a specification.

My invention has relation to a cap or holder for attachment to and movable about the incandescent mantle, burner or burners, and standard of the lamp, so that access may be had to the burner or burners of the lamp to regulate the same as required without removing the globe or without disturbing or destroying the mantles of the incandescent gas burner or burners of the lamp.

The nature, scope, and objects of my invention will be more fully understood from the following description, taken in connection with the accompanying drawings, forming part hereof, in which—

Figure 1 is an elevational view, partly in broken section, of an incandescent gas-burner lamp with a cap or holder embodying features of my invention shown in application thereto. Figs. 2, 3, and 4 are respectively transverse sectional views on the lines $x-x$, $y-y$, and $z-z$ of Fig. 1; and Fig. 5 is an elevational view of a modified form of cap or holder applied to an incandescent gas-burner lamp, showing in this instance the cap or holder provided with a sliding door for obtaining access to the burner or burners of the lamp, so as to adjust or regulate the burner or burners without affecting or destroying the mantles employed with the burner or burners in the manner, for example, as illustrated in Fig. 1.

Referring to the drawings, A is the globe of the lamp, adapted to be suitably supported in position and provided at the contracted base with a curved rim or flange a.

B, B', B², and B³, Figs. 2 and 3, represent a series of burners mounted in the lamp and carrying in supported position about the same mantles b', b², and b³, of incandescent material.

C is the gas-inlet pipe, extending downward centrally through the lamp and by means of branches c, c', c², and c³ connected

with the series of burners of the lamp, this inlet-pipe being extended some distance below the burners of the lamp and capped at c⁴ and which extension forms a standard c⁵ for a spider-frame d of the cap or holder D of my said invention to such lamps, which spider-frame d is held to the standard c⁵ by means of a tightening-screw d'. The cap or holder D is made, preferably, tapering in shape from the spider-frame d thereof to the upper end and is provided with tightening or thumb screws d² for engaging the flange or rim a of the globe A, as clearly illustrated in Figs. 1 and 2 of the drawings. The cap or holder D is provided with a door d³, hinged at d⁴ with a sliding locking-catch d⁵, as illustrated in Fig. 1, while in Fig. 5 the door is sliding back and forth on the surface of the cap or holder D. The said cap or holder D is so arranged, as described, as to be turned on the flange or rim a of the globe A, and when the door in either form is open access may be had to the series of burners of the lamp and to the mantles suspended above the burners for adjusting or regulating the flames of the burners with respect to the mantles, so that a proper degree of incandescence may be derived from the mantles induced by the ignited gas of the burners and also preventing deterioration of the mantles or charing thereof from lack of the proper quantity of flame from the burner or burners.

Having thus described the nature and objects of my invention, what I claim as new, and desire to secure by Letters Patent, is—

1. In a globe-holder for gas-burners, a standard forming a gas-inlet, a burner or burners connected therewith, a globe, a cap or holder having a movable door, said cap or holder provided with a spider-frame and clamping devices, certain of said devices engaging said globe and one of said devices engaging said standard, substantially as and for the purposes described.

2. In a globe-holder for gas-burners, a standard forming a gas-inlet, a burner or burners connected therewith, a globe, a cap or holder provided with a spider-frame, clamping-screws and a movable door, the clamping-screws of said frame and cap or holder adapted to permit of the turning of said cap or holder on

said globe and on the standard of said gas-inlet, substantially as and for the purposes described.

3. In a globe-holder for gas-burners, a stand-
ard forming a gas-inlet, a burner or burners
connected therewith, a globe, a cap or holder
having a hinged door and clamping-screws
and spider-frame having a clamping-screw
adapted to engage said standard below the
gas burner or burners to support said cap or

holder and globe, in required position, sub-
stantially as and for the purposes described.

In testimony whereof I have hereunto set
my signature in the presence of two subscrib-
ing witnesses.

GEORGE F. KLEMM.
